BAGGAGE-RACK.

1,139,868.

Specification of Letters Patent. Patented May 18, 1915.

Application filed March 8, 1911. Serial No. 613,017.

To all whom it may concern:

Be it known that I, FRANK E. HOWARD, a citizen of the United States, residing at Hartford, in the county of Hartford and State of Connecticut, have invented new and useful Improvements in Baggage-Racks, of which the following is a specification.

This invention relates to baggage racks for railway passenger coaches, and comprises improvements in the construction and arrangement of said racks, whereby their manufacture and assembling is improved, simplified, and reduced in cost; without impairing their capacity for withstanding the strains incident to their use.

In designing baggage racks of this character for use in passenger coaches, it is desirable to provide for making them in standard units, which without any change in the form or manufacture may be employed either as single separate racks disposed at intervals along the wall of the car, or as continuous racks firmly connected together and extending continuously along the wall. It is also desirable to make the different and separable units as few as possible, with the least practicable number of extra and special fastenings or other small parts, which are liable to be lost, or misplaced in assembling. It is also desirable, even when making the parts symmetrical in external appearance, to provide for making the outer side of the rack stronger and more firmly secured together than the portion thereof which is next to the wall, since it is the outer portion which is subjected to the greatest weight and severest strains when in use.

The present invention makes it possible to properly design and proportion the parts, and to provide for their secure assembling and fastening together, with due regard to this relative severity of use of the different parts. Advantage is taken of the fact that the rearward main supporting member of the rack bottoms does not need to be as stiff or as strong as the front member; also that it does not need to be tied to the brackets as does the front member, on account of the fact that the wall of the car, to which the brackets must be securely fastened, serves as a tie member for holding together the feet of the brackets, against the rearward ends of the rack bottoms. In connection therewith provision is made for preventing

the reversal of the rack bottoms from front 55 to rear in assembling them on the wall of the car, and in restoring them to place after being removed for repairs or for any other purpose. Hence, according to the present invention, while the front, main supporting member of the rack bottom may be a solid rod, or a reinforced tube, the main supporting rear member may be of much lighter construction, either by using a smaller rod, or thinner tubing, with or without any inner reinforcing rod. Moreover, there being no necessity for utilizing the rearward main members as tying members between the brackets, since the closely adjacent feet of those brackets are held together by the car wall, the endwise or tying connection is dispensed with, and a plain, simple socket connection is employed between the ends of the rear member and the side faces of the bracket. Furthermore, in 70 order to prevent the aforesaid reversal of the rack bottom from front to back, which would defeat one of the main purposes of the invention, the attaching joints between the rearward members of the rack bottom 75 and the bracket are made entirely different from the attaching joints between the front members of the rack bottom and the outer ends of the brackets, the sockets or seats for the rearward members being preferably 80 made imperforate to prevent the insertion or use of any tie-rods or studs, or other means which may be employed at the outward end of the brackets for tying them together lengthwise of the car.

Figure 1 of the drawings is a plan view of a complete section, and another partial section of one of these improved racks. Fig. 2 is a side view of one of the wall brackets, projected from Fig. 1. Figs. 3, 4, 5 and 6 are fragmentary views in enlarged scale, and partly in section, showing different forms of the improved socket connection between the wall brackets and the rearward longitudinal member of the rack bottom. Figs. 7, 8 and 9 are plan views also in enlarged scale, and partially in section of modified tying connections between the outer ends of the wall brackets and the front longitudinal members of the rack bottoms. Fig. 10 is 105 an end view projected from Fig. 9, and Fig. 11 is a rearward view in section taken on the line 11—11 of Fig. 10, showing a modi-

fied construction of the outer end of the wall brackets and their connection with the front member of the rack bottom. Fig. 12 is a plan view also in enlarged scale, showing 5 a method of completing the joints on the outer sides of the outer ends of the wall brackets.

The principal units herein employed are only two in number,—the rack bottoms, designated in a general way by A, and the brackets B. The feet of the brackets are secured to the wall C of the car by means of suitable bolts or screws, and are provided with bosses 5 and 6 for receiving and supporting 10 the ends of the rack bottoms A. The rack bottom units A are made in a unitary structure, the main supporting members of which are the front longitudinal member 8 and the rearward longitudinal member 9, the ends of which connect with and are supported by the bosses 5 and 6, respectively of the brackets B. The basket or grill portion of the rack bottoms A may be made up in various ways. They are here- 15 shown to consist of the longitudinal rods or tubes 10 connected with each other and with the front and rear members 8 and 9 by means of cross-bars 11. These rods and cross-bars form an open floor for the rack, 20 upon which the pieces of baggage rest. They are fastened together so as to constitute a firm and unitary structure, which, like the brackets B may be duplicated to any desired extent by uniform processes of manufacture, and in transportation, assembling 25 and the making of repairs, are handled and treated as a single piece.

The ends of the rearward member 9 are connected with the bosses 6 of the brackets 40 by a simple socket joint in either of the ways illustrated in enlarged scale in Figs. 3, 4, 5 and 6. In Figs. 3, 5 and 6, the ends of the members 9 project into seats recessed in the sides of the bosses 6 of the brackets, 45 while in the form shown in Fig. 4, the tubular ends of the members 9 fit upon the exterior of the bosses 15. These recesses and bosses may be made upon one side of the bracket only, as shown in Figs. 5 and 6, in 50 cases where the baggage racks are only to be used singly. But where there is any likelihood that the racks are to be joined together, in a continuous form, as shown in Fig. 1, the brackets are uniformly provided 55 with socket connections for the rear members 9 upon both sides of the bracket, as shown in Figs. 3 and 4.

Obviously, either the front members 8, or the rear members 9 may be made either 60 solid or tubular; and in the latter case the ends of the tubes may be open as shown in Figs. 3 and 4; or they may be closed at their ends, as shown in Figs. 5 and 6. In Fig. 5, the end of the tubular member 9 is closed 65 by means of a hollow cup or thimble 13,

while in Fig. 6 the end of the tube is closed by means of a solid plug 14. In Fig. 4 the ends of the tubular members 9 are supported by the bosses 15, which extend within the tube, and thus not only support the tube, 70 but serve, like the filling pieces 13 and 14, to prevent the ends of the tube 9 from collapsing. In each of these instances, the rearward member 9 of the rack bottom is merely slipped upon or into the bosses correspond- 75 ing to the bosses 6 of the brackets, which therefore support the rear members against lateral displacement only, the wall of the car serving to hold the brackets together, and thus preventing the spreading movement 80 which would release the ends of the members 9.

In the case of the outer or front side of the rack, however, the conditions are entirely different. Here it is desirable not only 85 to make the rack members 8 of greater lateral strength, but it is also desirable to connect them with the outer ends of the brackets by a tying joint, to prevent spreading movement of the outer ends of the brackets. 90 Therefore, the front members 8, although they may be of the same size as the rearward members 9 for symmetry of appearance, are preferably of much stronger construction, either of solid rods or reinforced tubing. As 95 these baggage racks are generally of brass or bronze finish, it is customary and desirable to employ brass or bronze tubes for these front members, reinforced by steel rods, as herein shown, to insure proper stiffness, and to fasten their ends to the front ends of the bracket by means of screw-threaded connections seated in eyes in the bosses 5, as shown in Figs. 7 and 12, or by means of button-head or T-head rods fitting 100 in corresponding T-shaped grooves or slots in the side faces of the brackets, as shown in Figs. 9, 10 and 11.

In Fig. 7, the ends of the front members 8 are shown to be supported in recessed seats 110 in the side faces of the bosses 5 of the brackets; and the ends of the interior reinforcing rods 17 are threaded to receive a double-ended stud 18, which serves to tie the ends of the rods 17 and the members 8 115 firmly to the sides of the brackets, thus preventing their spreading movement and the consequent release of the ends of the members 8.

In Fig. 8, the ends of the interior rods 120 themselves are screwed together, one within the other, thus drawing the ends of the members 8 against the side faces of the bosses 5, which in this case are not shown to be recessed. In Fig. 9 the ends of the tubular members 8 also abut against the outer faces of the bosses 23, while the ends of the reinforcing rods 22 are shown to project beyond the ends of the tubes 8, and are provided with button or flange-shaped heads 24, which 130

are seated in correspondingly undercut T-shaped slots or grooves 25, cut in the side faces of the bosses 23. The openings leading to these T-shaped seats preferably extend 5 toward the rearward side of the bracket, leaving the outward or front surface of the ends of the brackets smooth.

In Fig. 12 is shown a preferred method of securing the outer sides of a pair of 10 brackets together when used in connection with a single rack, or of securing the end brackets in the case of the continuous rack shown in Fig. 1. A nut 27 is screwed upon a projecting threaded extension of the 15 reinforcing rod of the front member 8, which in this instance is shown to be a double-ended stud 28, like the stud 18 of Fig. 7. In the construction shown in Fig. 8, the nut 27 may be screwed upon the threaded end of 20 the reinforcing rod 20. In the construction shown in Figs. 9, 10 and 11, no such nut is needed. In that case also the T-slot 24 may be omitted from the outer sides of the 25 paired brackets of a single rack, or the end brackets of a continuous rack, where so desired. As a general rule, however, it will be found preferable to make all brackets alike, where there is any possibility that they may be set up as continuous racks.

30 In assembling single racks of this character, the brackets are simply put in position upon the ends of the racks, and then screwed to the wall. In setting up a continuous rack, an end bracket is first screwed to place, then 35 the ends of a rack bottom are inserted, the next bracket is placed upon the other end of the rack bottom and screwed to the wall; then another rack bottom, and another bracket, and so on. The ends of the outer 40 rack bottom members 8 are secured to the respective brackets when the latter are fastened to position, and before putting the next rack bottom in place. On account of the differences in the seats for receiving the 45 front and rear members of the rack bottoms, there is no danger of the rack bottoms being assembled in reverse position, that is with the front at the back, although they may be freely reversed end for end. In instances where the front and rear seats in the 50 brackets B may otherwise be alike, as in Figs. 7 and 3, the imperforate condition of the seat at the rearward side of the bracket would prevent the insertion of the stud 18, 55 or the threaded end of the rod 20 in that rearward seat, thus also making it impossible to reverse the racks from front to back.

Any of the seats shown in Figs. 3, 4, 5 and 6, for the rearward longitudinal member 9 60 of the rack bottom, may be employed upon the same bracket with any of the seats for the front member 8 shown in Figs. 7 to 11, inclusive. The preference thus far indicated by my experience is for a recessed rearward 65 seat like that shown in Fig. 3, in combina-

tion with a front seat and tie-rod like that shown in Fig. 8. I also consider it preferable to plug the ends of the rearward member 9, as shown in Figs. 5 or 6, thus rendering the ends of the rearward member 9 imperforate as well as the seat therefor in the bracket B, thereby preventing the accidental or inadvertent insertion into the rearward member 9 of the reinforcing or tie-rods 17, 70 20 or 22, intended only for the front rack 75 member 8.

In all these cases separation between the outer ends of the brackets and the ends of the front members of the rack is positively prevented by non-slipping shouldered connections formed by the flanged or button heads in the construction shown in Fig. 9, and formed by the threads of the screws in the other instances illustrated. Separation or retraction of the rearward members of 80 the racks from their socket connection with the brackets is prevented by the fact that the brackets are fastened to the wall of the car; so that it is not possible for the racks to fall out of place or to be detached or released 85 from place either purposely or inadvertently, except by taking down the brackets. Although it is not without advantage to have the rack sections removable without taking down the brackets, yet the construction 90 which permits such removal is necessarily more expensive. Moreover, in repairing or refinishing these racks, it is generally found necessary to repair and refinish the brackets also, for which purpose they must 95 be removed from the wall of the car. The present invention therefore provides a rack 100 of simple and inexpensive construction, which is positively and irremovably retained in position in the brackets while the 105 latter are in position on the wall; and when used in a continuous rack the sections serve through their positive shouldered connection with the outer ends of the brackets to tie the latter together so that the sections mutually 110 contribute to the firmness of the structure.

I claim as my invention:—

1. The combination, in a baggage rack, of wall brackets, a rack bottom made in a unitary structure, including a non-extensible 115 rear member, socket joints directly connecting the said wall brackets with the ends of the rear member, preventing displacement of said rear member in any lateral direction, and a longitudinal front member, the ends 120 of which have a shouldered tying connection with the outer ends of the wall brackets.

2. The combination, in baggage racks, of wall brackets, a rack bottom made in a unitary structure having a substantial front 125 member, a less substantial rear member, direct socket connections between the ends of the rear member and the brackets, and means forming a positive tying connection holding the outer ends of the brackets 130

against the ends of the said front member of the rack bottom.

3. The combination, in baggage racks, of a rack bottom having a hollow tubular rear member, and an internally reinforced tubular front member, and wall brackets having direct socket connections with the ends of the said rear member and means for positively clamping the outer ends of the 10 brackets against the ends of the said front member.

4. In a baggage rack, the combination of a wall bracket, a rack bottom made in a unitary structure including non-extensible 15 longitudinal rail members, a socket joint connection between one of the rail members and a portion of the bracket preventing displacement of said rail member from said bracket excepting in a longitudinal direction, and a shouldered tying connection be- 20 tween another rail member and another portion of the bracket preventing longitudinal

displacement of said second rail member from said bracket.

5. In a baggage rack, the combination of 25 a wall bracket, a rack bottom made in a unitary structure, including longitudinal rail members, a socket joint connection between the rearward rail member and the base portion of the bracket preventing displacement of said rail member from said bracket excepting in a longitudinal direction, and a threaded connection clamping the end of the front rail member against the outer end of the bracket and preventing both 30 lateral and longitudinal displacement of the 35 said front member from said bracket.

In testimony whereof I have signed my name to this specification in the presence of two subscribing witnesses.

FRANK E. HOWARD.
